CLOSURE

Abraham Singer Karper, New York, N. Y.

Application August 5, 1931, Serial No. 555,176

5 Claims. (Cl. 220—37)

This invention relates to a structurally and functionally improved closure capable of use in numerous different associations but primarily intended for employment in connection with receptacles, and especially waste receptacles.

It is an object of the invention to provide a device of this character which under normal conditions will substantially seal a receptacle in such manner that entrance to and escape from the receptacle body by other than a deliberate actuation of the parts will be virtually precluded and in which, moreover, when it is desired to obtain access to the receptacle this may be accomplished with minimum effort.

A further object of the invention is that of providing a closure particularly intended for association with a waste receiving receptacle and in which the closure will open in virtually an automatic manner and will thereupon automatically return to receptacle-sealing position.

A still further object of the invention is that of furnishing a closure in which the parts may readily be adjusted so as to compensate for wear and/or to properly correlate the parts so that they may cooperate to obtain the best possible results.

Another object is that of constructing an apparatus of this character in which various classes of waste may be efficiently segregated and in which, additionally—if desired—the closure may in certain aspects perform the functions of or include a signalling structure.

Additional objects of the invention are those of providing a structure of this nature which will embody relatively few parts, each individually simple and rugged in construction, these parts being capable of ready assembly and application to either an old or especially designed receptacle to provide an apparatus operating over long periods of time with freedom from difficulty.

With these and other objects in mind, reference is had to the attached sheets of drawings illustrating practical embodiments of the invention and in which:

Fig. 1 is a sectional side view of one form of closure and receptacle;

Figs. 2 and 3 are similar views of different forms thereof;

Fig. 4 shows a still different arrangement of the invention;

Fig. 5 is a sectional side view of another form of closure and receptacle; and

Fig. 6 is an end view of such latter arrangement of the parts and showing certain of the same in elevation.

In these several views the numeral 10 indicates a receptacle of any desired material and configuration and upon which a cap member is disposed. Obviously, as will hereinafter appear to those skilled in the art, certain parts of the hereinafter described construction might be formed integrally or fixed with respect to the receptacle body. However, for convenience in manufacturing, as well as with a view to economy and ready separation of the parts when necessary, it is preferred that the cap and its associated structure be formed—as shown—to be wholly removable from the receptacle body.

Thus, the cap member preferably includes a base in the form of a ring 11 or any other configuration suitable for cooperation with the receptacle edge and which ring is to overlie and extend adjacent to the upper edge of the receptacle. To retain the same in position, a flanged element 12 is secured in spaced relationship to the ring and such spacing defines a recess suitable for the reception of the upper receptacle edge. As shown, the flanged member 12 may support a crossbar 13 and this crossbar conveniently mounts a post 14. With a view to providing a proper seal and guiding lip, the member 11 may be extended inwardly and upwardly as at 15 and then inwardly and downwardly as at 16, and terminate in a flanged portion 17.

Disposed above the ring member 11 is a closure element in the form of a truncated cone 18. Obviously, however, in lieu of this specific configuration any properly shaped element may be employed.

Now, with a view to maintaining the closure 18 in proper relationship with respect to the remainder of the cap structure, it is preferred, according to the present invention, to employ a spring 19 which, as shown, may have its lower end closely encircle the post 14 and, as illustrated in Fig. 1, have its body beyond such post enlarged, as at 20. The upper end of the spring—again referring to Fig. 1—is again relatively constricted and encircles a post or rod 21 to have clamping contact therewith. Attachment of the closure 18 to this rod follows preferably by set screws 22, or any other suitable structure, by means of which the closure may be adjusted along a vertical axis.

Thus a closure is furnished in which a person by simply bearing against the element 18 may rock the same in any desired direction and upon securing adequate clearance between the edge of the element 18 and the ring member 11, dispose of the waste within the receptacle 10. Obviously

this receptacle may accommodate an inner receptacle which is readily removable through a side door in the body 10 (not shown) so that ready disposal of the waste contents is practicable. If it is desired to produce a complete unit which may be readily moved about with a minimum of noise, the body 10 may be provided at the bottom with rubber tire rollers, as indicated at 50 in Fig. 1. Upon the element 18 being released, 5 it will, under the influence of the spring 20, return to its normal position whether in such displacement it has been simply rocked or forced sidewise. Adjustments for variation in flexion strength of the spring 20—or its equivalent—may 10 be made by means of the set screws 22 or their equivalent, and if desired, to prevent to a maximum extent the escape of odors from the receptacle or ready access into the interior of the same, a packing strip 23 may be secured to the flange 15 20 and have sliding contact with the inturned edge portion 24 of the closure. Under usual circumstances, however, it is preferred, as illustrated in Fig. 3 et seq. that the packing strip—which may be of rubber or any other material— 25 be secured to the flange 25 of the closure cap and have wiping engagement with the inwardly and downwardly extending portion 16 of the ring member. If such a structure is employed it will be seen that any difficulties in connection with 30 waste matter catching against the packing strip will be avoided.

As shown in Fig. 2, under certain circumstances it may be desirable to produce a closure unit in which adjustment of the clearance of the element 18 may be accomplished by either employing the set screws 22 or by adjusting the nuts 51 which hold the post 14 in place. It is, of course, apparent that both post 21 and post 14 might be formed of hollow tubing so that a direct entrance 40 into the interior of the can would result and small objects could be disposed through the post 21 and would travel downwardly through the inner area of the spring 20 and the hollow portion of the post 14, and thus reach the interior of the can. 45 In some instances it has been found desirable to provide a closure of this type which may be opened and waste matter disposed by the use of one hand only. One way of accomplishing this, as shown by Fig. 2, is to provide a rail member 50 55 which is spaced from and encircles the element 18 and is secured thereto by braces 53. By this expedient a person wishing to deposit waste within the can would simply bear against the rail member with the hand in which he held the waste material, and after effecting an opening of the closure would release his grasp on the waste material and allow the same to fall into the body of the can through this space between the rail member and the element 18. 60 In the form of construction shown in Fig. 3, the closure embraces cap elements 26 and 27 which are proportioned and arranged to provide a unitary structure. In this instance the post 14 is in the form of a tube 28 which supports the 65 spring 29 but below which a receptacle 30 is removably positioned. Also, in this form of the invention the spring 29 defines a tube portion, the upper end of which underlies and is secured to a funnel member 31 which may form an integral part or—as shown—be fixedly secured to cap element 27. In this case the member 31 will 70 also provide a cross-bar or its equivalent 32 which will mount a secondary post 33, in turn supporting a spring 34, corresponding functionally and structurally to the springs 19 and 20. Similarly 75

to the structure of the latter, the upper end of the spring will bear against a post 35, to which the cap element 26 is adjustably secured in any desired manner.

With a structure of this nature it will be obvious that waste products, such as cigarettes, cigars and similar small articles may be disposed of by simply rocking or shifting the element 26 to a point at which access to the funnel member 31 may be had. These waste products will—under 10 the action of gravity—move across this member and through the open base or openings thereof into the tube defined by the spring 29 and thus through the tube 28 into the receptacle 30. On the other hand, larger articles may be disposed of by simply shifting the element 27 to a point at which they may enter the body of the receptacle 10. Similarly to the structure shown in Fig. 1, they may then fall into a separate waste receptacle (not shown) so that they may be readily removable as a unit from the body of the container 10. 15

It is apparent that the structure shown in Fig. 3 might be duplicated indefinitely to provide any desired number of closures with which separate 20 or single waste receiving receptacles might be connected. However, for the purpose of avoiding undue illustration, no showing of a plurality of more than two superposed closure elements has been attempted in the annexed drawings. 25

Under similar or other circumstances it might also be desired to have the closure function with or without the receptacle portion as a signalling medium. This has been shown in Fig. 4 in which the post indicated at 35 in Fig. 3 has been continued as at 36 and mounts at its upper end a signalling device 37 of any desired configuration. With such a construction an apparatus is furnished which, whether used in connection with, or divorced from, a receptacle, will serve the 30 functions of a "silent policeman" which will have the additional advantage that if struck by a passing vehicle it will give under the force of a blow and thereupon forthwith return to its normal position. Of course, under these circumstances 35 it might be desired—if a receptacle is employed—to sink the latter into the supporting surface to a point indicated in the figure in question. 40

In certain instances it may be desired to effect 45 an opening of the closure other than by directly engaging the same with the hands or with the matter to be disposed of. Under these circumstances, and as shown in Figs. 5 and 6, a treadle 50 55 60 65 70 75 80 85 90 95 99 38 may be pivotally attached to the receptacle and serve to actuate a lever 39 within the same. This lever will conveniently actuate rods 40 secured to a crossbar 41. The latter is attached to a vertically extending arm 42 forming a part of a pivot bar 43 supported by the receptacle. The upper end of the arm 42 is attached, for example, by a pivot 44 to the flanged member 46 of the funnel member 31. Rods 45 connect to a member 46 and the crossbar 41. Consequently when the ring 38 is rocked the rods 40 transmit this effect to the bar 41 which in turn exerts a rocking and shifting force on to the funnel member which is fixed with respect to the closure element 27. Therefore, the latter, together with its associate structure, will rock with respect to the receptacle 10. An access may thus be had between the ring member and the closure element without being necessary to deliberately engage the latter.

It is, of course, apparent that the treadle 38 might directly couple with the closure element 27 by means of rods or otherwise, but where such

an expedient is resorted to, it becomes difficult to dispose a container of adequate size within the receptacle without interference with the rods or associated structures.

5 In addition to its primary function the post 14 serves to restrict the area of flexibility of the spring 20, which spring may be secured directly to the cross member 13 or its functional equivalent. By lengthening or shortening the post, it is possible to produce a closure which will swing through a greater or shorter arc when the same is opened, and additionally the ruggedness of the device is increased by increasing the length of this element.

15 From the foregoing it will be understood that among others, the several objects of the invention as specifically aforenoted are achieved. It is apparent that numerous changes in construction and rearrangements of the parts may be resorted to without departing from the spirit of the invention as defined by the claims.

Having described my invention, what I claim as new and desire to secure by Letters Patent is:

1. A closure including a base, a spring extending therefrom, a cap element, a funnel member mounting said element and secured to said spring, a second spring secured to said member and a second cap element mounted by said latter spring.

2. A closure including a plurality of juxtaposed cap elements, a positioning ring associated therewith, a hollow resilient member securing the lower of said elements to said ring and serving as a tube, and means for movably mounting the second of said cap elements above said hollow resilient member to normally seal the upper end thereof.

3. A container including, in combination, a body portion, a plurality of juxtaposed cap elements for normally sealing the upper end thereof, a hollow resilient member for securing the lower of said cap elements in position over said container body, a secondary receptacle disposed within said container body and secured to the lower end of said hollow resilient member, and means for movably mounting the second of said cap elements above said hollow resilient element 10 and in position to normally seal the upper end of the latter.

4. A closure including a base, a plurality of juxtaposed cap elements, means extending from said base and acting to support said elements 15 whereby the lower element is rendered movable with respect to said base and said other element, and additional means movably supporting the second of said elements whereby it is rendered movable with respect to said base and with respect to the lower of said cap elements.

5. A container of the character described comprising a body portion, a plurality of cap members normally sealing the same, resilient means for positioning the lowermost of said cap elements in movable sealing contact with the top of said container body, said resilient means comprising a hollow tubular member, means for securing an additional cap element above said first named cap element and in contact with the upper end of said tubular element, and further means for varying the intimacy of contact of said uppermost cap element with respect to the upper end of said tubular member.
